US0D1015361S

(12) **United States Design Patent** (10) **Patent No.:** **US D1,015,361 S**
Jeon (45) **Date of Patent:** **** Feb. 20, 2024**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventor: **Jinhee Jeon**, Suwon-si (KR)

(73) Assignee: **SAMSUNG ELECTRONICS CO., LTD.**, Suwon-si (KR)

(**) Term: **15 Years**

(21) Appl. No.: **29/784,393**

(22) Filed: **May 19, 2021**

(30) **Foreign Application Priority Data**

Dec. 30, 2020 (KR) 30-2020-0065942

(51) **LOC (14) Cl.** **14-04**

(52) **U.S. Cl.**

USPC **D14/485**

(58) **Field of Classification Search**

USPC D14/485-495

CPC G06F 3/048-04897

See application file for complete search history.

(57) **CLAIM**

The ornamental design for a display screen or portion thereof with graphical user interface, as shown and described.

DESCRIPTION

The FIGURE is a front view of a display screen or portion thereof with graphical user interface showing my new design.

The outer perimeter shown in broken lines in the FIGURE illustrates a display screen or portion thereof and forms no part of the claimed design. The remaining broken lines in the FIGURE illustrate portions of the graphical user interface that form no part of the claimed design.

1 Claim, 1 Drawing Sheet
